UNITED STATES PATENT OFFICE

ERNEST H. SHAFF, OF GRAND HAVEN, MICHIGAN, ASSIGNOR TO WM. H. KELLER, INC., OF GRAND HAVEN, MICHIGAN, A CORPORATION OF MICHIGAN

PRESSURE-FLUID MOTOR

Application filed February 16, 1925. Serial No. 9,392.

This invention relates to pressure fluid motors and particularly to motors of the type disclosed in my copending application Serial No. 743,205, filing date October 13, 1924.

In said application I have described and illustrated a hand held motor device in which a rotary tool is operated by a compressed air motor comprising a circumferentially arranged group of pistons and cylinders acting upon a series of combined bell cranks which operate to impart a gyratory motion to a pin or arm moving in a conical path. The gyratory motion serves to produce the desired rotation of the tool and likewise to operate a rotating valve member which controls the admission and the exhaust to the cylinders.

It is an object of this invention to provide an advantageous construction for the rotating and gyrating parts of the device whereby to minimize the wear on these parts and simplify their manufacture so that the tool may be manufactured on an economical basis.

Another object of the invention is to provide an improved driving relation between the valve member and the rotating structure.

Still another object is to provide an advantageous construction for the gyrating portion and for the means by which gyration is converted into rotation.

Still other and ancillary objects and advantages of the improved structure will be apparent from the ensuing description of the device illustrated in the accompanying drawings, in which

Figure 1 represents a longitudinal cross section of the device as a whole.

Fig. 2 is a vertical cross section of the device along the line 2—2 of Fig. 1 showing the arrangement of the cylinders and of the end of the valve member.

Fig. 3 is a detailed cross section of the valve member on the line 6—6 of Fig. 1.

Fig. 4 is a detailed enlarged view of the connection between the driving shaft and the valve member, the cross section being shown in a horizontal plane of the device as shown in Fig. 1.

Fig. 5 is a perspective view of the driv-

ing yoke connecting the drive shaft and the valve member.

Fig. 6 is a view of the rear portion of the device taken on the line 6—6 of Fig. 1.

Fig. 7 is an end view of one of the plates 55 constituting the bell crank.

Fig. 8 is a face view of the plate shown in Fig. 7.

Fig. 9 is a face view of a plate complementary to that shown in Fig. 8.

Fig. 10 is a cross section of the plate of Fig. 9 on the line 10—10 thereof.

Fig. 11 is a cross section of the device taken substantially on the line 11—11 of Fig. 1 showing the bell crank plate in elevation at 165 an angle to the vertical.

General description

Referring first to Fig. 1 of the drawings, 10 designates the annular casing of a portable grinder comprising a main or rear section 11 and a front section 12. The rear section is closed by means of a plate 13 with which is rigid a handle 14. Within the rear or main section of the casing is a plurality 70 of motor units arranged in circular series, each comprising a cylinder 15 and a piston 16. The flow of fluid pressure to and from these several motor units is controlled by an automatically operating valve mechanism, 75 generally designated by the numeral 17 and by a manually operable valve in the handle generally designated by the numeral 18.

Power impulses imparted to the pistons of the several motor units are successively transmitted by piston rods 19 to a plurality of bell cranks arranged in a circular series and formed by a crank plate 20 and a crank arm 21, said arm constituting in effect an arm 80 common to each bell crank of the series, the other arms being embodied in the plate 20. The crank arm 21 is connected to a second crank arm 22 rigid with a tool spindle 23 which is journaled in the forward section 90 12 of the casing. The plate 20 is secured rigidly to the crank arm 21 forming a structure which is provided with a pivotal relationship to the crank arm 22 producing in effect a shifting fulcrum for each bell crank 95 100

continuously moving with the crank arm 21 common to each of the bell cranks.

In the present invention the improvements over the device disclosed in the above mentioned application relate to the rotary construction within the casing 10. As above pointed out, the rotary construction includes the valve 17, bell crank plate 20, the common bell crank arm 21, and the spindle 23 with its crank arm 22 in rotary relation to the bell crank arm 21.

The valve 17 is operated by the rotary construction. The main or rear section 11 of the tool casing is annular in form and in the present instance is cast to form integral therewith a cylinder block 24 which is bored to receive sleeves forming a circular series of cylinders 15. The annular opening of the cylinder block in part houses the valve mechanism 17.

Integral with the rear plate 13 of the casing is a rearwardly extending tubular portion 27 constituting a hub for the valve mechanism 17 and providing a support to which the handle 14 may be secured, the handle being in this instance shown as formed integrally with the portion 27.

The valve mechanism 17 which I by preference employ, comprises a stationary casing 28 having a series of circumferentially arranged slots forming ports 29 which communicate with passages 39 formed in enlargements 40 integral with the plate 13 (Figs. 1 and 6). The passages 39 are inclined forwardly and outwardly and at their forward ends open into the rear ends of the cylinders 15. Within the valve casing 28 is a rotary valve member 41 having at its rear end an annular groove 42 from which a plurality of port holes 43 (Figs. 1 and 3) which extend forwardly and terminate in a transverse slot 44 formed in the periphery of the valve member, said slot being positioned approximately centrally thereof so as to register successively with the ports 29. The valve member also has a central bore 45 opening at its forward end into a transverse slot 46 located diametrically opposite the slot 44 and also adapted to register successively with the ports 29. The annular groove 42 (Fig. 1) communicates at all times with a passage 47 in the handle to which motive fluid is supplied under the control of a manually operable valve 18 so that in the rotation of the valve member, pressure is admitted successively to the circular series of ports 29 by way of the holes or ducts 43 and the transverse slot 44. On the other hand, the bore 45 communicates at its rear end with an exhaust passage 48 extending radially outwardly into an exhaust chamber 49 which is opened to the atmosphere so that as the slot 46 registers successively with the ports 29, communication is established between the cylinders and the atmosphere.

Bearing in the annular opening of the cylinder block 24 through the medium of a ball bearing 51 is a rotary shaft 50. The shaft 50 is screw threaded near the end as shown at 52 in Figs. 1 and 4 and carries a pair of nuts 53 and 54 which hold the bearing 51 against a shoulder 55 formed in the cylinder block opening. The end of the shaft is reduced in diameter at 56 and the end has a diametrical slot 57 formed therein. The valve member 41 is axially bored, forming a hole 58 into which the end 56 of shaft 50 loosely projects leaving an annular space 59. The annular end of the valve member 41 is diametrically slotted at 60, the slot being of the same width as the slot 57 in the end of shaft 50. A yoke lying in the slots of both members provides a driving connection between the valve member 41 by the shaft 50. The yoke (Fig. 5) is flat and substantially U-shaped having the base 61 lying in the slot 57, the sides 62 lying in the annular space 59 and having outwardly projecting ears 63 which lie in the slot 60 in the valve member. A second pair of slots 64 is provided in the valve member 41 similar to the slots 60 and angular thereto to permit registry in a different axial relation of the shaft 50 with the valve member 41 for reversing the direction of rotation of the tool.

In the present instance the spindle 23 and the shaft 50 are axially aligned and rigid in structure. Within the front portion 12 of the casing the integral structure contains an offset section hereinabove referred to as the crank arm 22. By construction it is a section of the shafting 50-23 which is made angular to the shaft 50 in such a manner that the angular section or crank arm 22 describes a cone in the rotation of the spindle 23. The spindle 23 is housed in a tubular extension 12' of the casing 12 and turns in roller bearings 65 and 66. The end 67 of spindle 23 is rigidly associated with a collar 68 which is substantially an extended portion of the shaft 50. The collar 68 bears directly in the bearing 66. Collar 68 is provided with an annular shoulder 69 which abuts the inner race of the bearing 66. The material of collar 68 provides an irregular shaped strengthening flange in which the bearing shoulder 69 is formed. In Fig. 1 the flange at the bottom is shown of considerable thickness and of considerable radial extent being indicated at 70. Such a construction provides a mass of material which is arranged to counterbalance the weight of the offset section of the shaft, thereby reducing any tendency toward vibration of the device during rotation. The upper part of the flange is thinner and narrower in radial extent and merges into a flange 71 at the end of the angular portion or crank arm 22.

Crank arm 22 serves as a pivot for a surrounding sleeve 72 which contributes to the

formation of the crank arm 21 hereinabove referred to as common to the series of bell cranks, whose other arms are embodied in crank plate 20. The sleeve 72 is arranged to be rigidly associated with a bevel gear 73 which in the present instance is a separate structure from the sleeve. The rigid structure including sleeve 72 and gear 73 has ball bearing engagement with the crank arm 22. At one end the flange 71 is formed into a ball race while the end of the sleeve is cupped at 74 to form the other race for the balls 75. The rear end portion of the crank arm 22 has an enlarged section or flange 76 which is shaped to form a ball race facing the ball race of flange 71. The gear 73 has a ball race complementary to that of flange 76 for the balls 77. Sleeve 72 is externally threaded and is arranged to be screwed into a threaded opening in gear 73 for rigidly connecting the two together. A nut 78 also threaded on the sleeve serves to lock the sleeve 72 and gear 73 together. It will be observed that the present arrangement of the ball races requires that the sleeve 72 be screwed into the gear 73 to contract the length of the gear sleeve or crank arm 21 for the purpose of assembling the balls in their races. Hence, in the rigid construction disclosed in Fig. 1 there is a space 79 between the end of sleeve 72 and the inner part of the gear.

In accordance with the principle of operation of this device as fully set forth in the above mentioned application, the plate 20 must not rotate with respect to the casing, but must merely wabble about therein as the crank arms 21 and 22 gyrate. As in the device of the aforementioned application, the plate 20 is fixed against the undesirable rotation by a geared relationship with the casing forming in effect a universal connection therewith. This is accomplished by fixing plate 20 to gear 73 and meshing gear 73 into a corresponding bevel gear 80 fixed into the casing. The gear 80 is provided with a sleeve portion 81 which surrounds shaft 50. Gear 80 is fixed and non-rotatable in the casing by any suitable method as by the clutch teeth 81a (Figs. 1 and 11).

In the application of my invention to portable tools such as grinders or drills, as herein shown, it is necessary that the motor shall operate at high speed. I have found in this connection that the provision of spaced bearings between the crank arm and the wobbling unit as above set forth is of primary importance. Thus, these bearings serve not only to mount the wobbler unit so as to permit relative rotation between it and the crank arm with a minimum of frictional resistance, but they serve to maintain a proper operative relation between the gears 73 and 80, holding the gear 73 in such position as to prevent a complete intermeshing with the gear 80 and thus preventing a grinding action between

the gears. As shown in Fig. 1, a slight clearance is maintained between the crowns of the teeth of one gear element and the valleys of the teeth of the other gear element.

The plate 20 is made rigid with the crank arm 21 by providing it with a flange 82 clamped between the gear 73 and its lock nut 78. The form of plate 20 is illustrated in Figs. 9 and 10. Flange 82 is made on a tubular portion 83 struck from the plate 20 forming a recess into which gear 73 fits as shown in Fig. 1 in cross section. The plate is pentagonal in shape because of the provision of five cylinders 15 in the device. Each corner of the plate has a hemispherical depression 84 for a ball 85 carried by each piston rod 19. A plate 86 (Fig. 8) complementary to plate 20 is provided to complete the bell crank plate structure. Plate 86 is provided with circular holes 87 at each corner and is provided with spherically curved flanges 88 about each hole. The corners of the plate are slotted at 89 forming an entry into the holes 87 through which the piston rods 19 may be inserted. The edges of the plate are upturned at 90 to receive the slightly smaller plate 20. A central opening in plate 86 is formed to permit engagement of the bevel gears 73 and 80 therethrough. In Fig. 11 the two plates are shown in assembled and mounted relation, as by means of the nuts 91 threaded on the bolts 92 which pass through both plates. The piston rods are shown in cross section and the balls 85 are shown in elevation.

To provide an exit for pressure fluid leaking into the casing and to cool the rotating parts an exit is made through the rotating structure from the front to the rear of the device. This is accomplished by providing a continuous communicating passage therethrough comprising the openings 93 in crank arm 22, 94 through shaft 50 to the end thereof, the annular space 39 in the valve member, the extra pair of slots 64 in the valve member, an annular space 95 surrounding the lock nuts 53 and 54, and a passage 96 through the cylinder block 24 and the back plate 13.

By the above construction it is possible to make the ball bearings between the two crank arms 21 and 22 of a very small diameter. This is desirable because the device operates at high speed and in bearings of large diameter the peripheral speed of the balls would be so great as to cause excessive wear. In addition the construction provides a smaller number of parts which are capable of being economically manufactured and which are of such a character that they may be readily assembled into the device and replaced when sufficiently worn. Such a structure enables the manufacturer to produce an efficient device economically and to provide the user with a device which will at all times be capable of efficient operation by the simple re-

newal of parts when they are worn. The character of the parts permits such renewal at a small expense which is a desirable feature to the purchaser and user of such a device.

5 I claim as my invention:

1. In a device of the character described having a gyrating series of bell cranks, a shaft having its two ends alined and having an intermediate integral section offset at an angle thereto with its axis adapted to describe a cone in the rotation of the shaft, a sleeve pivoted about said section, said sleeve constituting an arm common to each of the bell cranks 10 of the series, and balls bearing in races formed directly in said shaft section and in said sleeve, said sleeve being adjustable to permit insertion and removal of said balls.

2. In a device of the character described 20 having a gyrating series of bell cranks, a shaft having its two ends alined and having an intermediate section offset at an angle thereto with its axis adapted to describe a cone in the rotation of the shaft, a sleeve-like structure about said section, said structure constituting an arm common to each of the bell cranks of the series, flanges on said section forming separated ball races facing each other, and means forming separated races in 25 said sleeve structure complementary to said other races, balls for the two sets of complementary races, one end of the sleeve structure having screw threaded relation with the other end to effect contraction of the sleeve for assembling the device.

3. In a device of the character described 40 having a gyrating arm and alined end portions integral therewith and rotating about an axis, a nonrotating sleeve on said arm, a pair of bearings interposed between said sleeve and said arm and each comprising a series of rolling elements, and means providing relative movement between bearing parts on said sleeve and arm to permit insertion and 45 removal of said elements while said sleeve is mounted on said arm.

4. In a device of the character described 50 having a gyrating arm and alined end portions integral therewith and rotating about an axis, a nonrotating sleeve on said arm, and a pair of bearings interposed between said sleeve and said arm and each including a series of rolling elements, said sleeve and said arm having a variable relation therebetween 55 while in assembled relation to permit insertion and removal of said elements.

5. In a device of the character described 60 having a gyrating series of bell cranks, in combination, a shaft, a crank arm rigid with said shaft at an angle thereto whereby the axis of said arm describes a cone in the rotation of the shaft, a sleeve-like structure about 65 said section forming an arm common to each of the bell cranks of the series, one end of said sleeve structure being screw-threaded

70 relatively with the other end to effect longitudinal adjustment of the sleeve.

6. In a device of the character described 75 having a gyrating series of bell cranks, in combination, a shaft, a crank arm rigid with said shaft at an angle thereto whereby the axis of said arm describes a cone in the rotation of the shaft, a sleeve-like structure about 80 said section, said structure forming an arm common to each of the bell cranks of the series, flanges on said section forming separated ball races facing each other, and means forming separated races in said sleeve structure complementary to said other races, balls 85 for the two sets of the complementary races, one end of the sleeve structure being screw threaded relatively with the other end to effect contraction of the sleeve to assemble the device.

7. In a device of the character described, 90 having, in combination, a casing, a driven shaft with an angular portion therein, a series of bell cranks having one arm in common, said common arm being sleeve-like in form and being relatively rotatable on said 95 angular portion, a bevel gear screwed onto said sleeve and being concentric therewith, means to lock said gear fixed to said sleeve, a second bevel gear fixed in said casing concentric with said shaft, and means to operate the bell cranks to rotate the shaft.

8. In a device of the character described 100 having a casing, a driven shaft within the casing, having an angular section therein, a series of bell cranks comprising, in combination, a sleeve rotatable on said angular shaft section, a bevel gear threaded onto said sleeve, a plate having a dished portion and a flange portion fitting over said bevel gear, a lock nut on said sleeve adapted to clamp the flange on 105 said plate between the nut and the gear, a bevel gear fixed to said casing concentric with said shaft, said sleeve being one arm in common for the bell cranks, and said plate embodying the other arms, and means to operate 110 the bell cranks to rotate the shaft.

9. In a device of the character described 115 having a gyrating arm rotating upon an axis, a gyrating non-rotating sleeve on said arm, two ball bearings between said sleeve and said arm, each bearing having one race thereof formed in said sleeve and the other race formed in said arm, one of said members being variable in length to effect mounting of the sleeve on the arm.

10. In a device of the character described 120 having a gyrating arm rotating upon an axis, a gyrating non-rotating sleeve on said arm, two ball bearings between said sleeve and said arm, the arm having two ball races facing each other, said sleeve having two ball races 125 facing away from each other, and said sleeve having a contractile construction whereby the races of the sleeve may be moved toward each other for mounting the sleeve on the arm.

11. In a device of the class described, in combination, a shaft having a main section and a section angular to the main section, and a pair of intermeshing bevel gears, each gear being annular in form, one gear being fixed concentrically with the main section of the shaft and the other gear bearing upon the angular section and providing a bearing ball race on the inner side.
12. A pressure fluid actuated tool comprising a casing, a plurality of motor units arranged in circular series in the casing, a shaft having an inclined part disposed on one side of its axis, a pressure member mounted in the casing between said part and said motor units and adapted for wobbling movement in the operation of said units, said pressure member including an outer annular ring with one side of which said motor units are operatively connected, an inner ring fitting into said outer ring from the other side of the latter, and bearing means including a thrust bearing interposed between said inner ring and said inclined part of the shaft.
13. In a device of the character described, the combination of an arm rotating upon a fixed axis, a wobbling non-rotating plate-structure mounted on said arm, said structure including a gear element rigid therewith, a stationary gear element angularly disposed with respect to the plane of said plate structure and coacting with the gear element on said plate structure to prevent rotation of said plate structure during the gyrating movements thereof, and a thrust bearing interposed between said arm and said plate structure and lying substantially within the plane of said plate structure to prevent a complete meshing of the gear elements.
49. In testimony whereof, I have hereunto affixed my signature.

ERNEST H. SHAFF.
